UNITED STATES PATENT OFFICE.

CHARLES D. WHITE, OF NORWICH, CONNECTICUT.

MACHINE FOR DYEING YARNS.

1,215,448.

Specification of Letters Patent. Patented Feb. 13, 1917.

Application filed August 31, 1915. Serial No. 48,151.

To all whom it may concern:

Be it known that I, CHARLES D. WHITE, a citizen of the United States, residing at Norwich, in the county of New London, in the State of Connecticut, have invented a certain new and useful Improvement in Machines for Dyeing Yarns, of which the following is a specification, reference being had to the accompanying drawings.

10 The immediate object of this invention is to provide a reasonably simple machine by means of which yarns may be automatically dyed, oxidized and washed, in continuous lengths and with absolute uniformity of color or shade; the white yarns being taken in at one end of said machine and the dyed yarns being delivered at the other end of said machine, wound upon beams, and ready for the next step in the operation of fabric making.

My said invention is clearly illustrated, both as a whole and as to its essential details, in the annexed drawings, Figure 1 being a side elevation of a machine embodying my present improvements and Fig. 2 is an elevation of the said machine as viewed from the opposite side, that is to say from the side where the driving mechanism is located, the beams at each end of the machine being removed. Fig. 3 is a plan view of said machine. Fig. 4 is a transverse sectional view taken on the line 4—4 of Fig. 1. Fig. 5 is an end elevation of the guide frame 33. Fig. 6 is a relatively enlarged end view of a pair of squeeze rolls. Fig. 7 is a perspective view of one of the pipes through which steam is sprayed into the tank.

Referring to these drawings the numeral 20 indicates an elongated rectangular tank which is divided, as here shown, by transverse partitions, into four disconnected tanks or chambers 21, 22, 23 and 24 and each of said chambers is provided with a water pipe 25 by means of which said chambers may be conveniently filled with water, and also with a steam-pipe 26 by means of which the water, dye, or other liquid contents of the chambers may be conveniently heated and agitated. Mounted upon the main tank 20 are relatively smaller tanks 27 and 28 for the storage of liquid dyes which are delivered into the proper chambers, by gravity, through discharge pipes 29 and 30, each discharge pipe being provided with a cock

or valve by means of which such discharge 55 may be properly regulated.

Referring now to Fig. 1, the numerals 31 denote beams of white yarns ready to be dyed. From the beams 31 the yarns pass upward through guide eyes 32 in a bar 33 which is, preferably, suspended from overhead. The yarns then pass to a frame 34 in which are mounted slats 35 which serve to guide the yarns to similar slats 36 located at the end of tank 20, which last named slats 65 are so spaced apart from each other that the yarns are kept from engagement, and entanglement, with each other as the yarns enter the chamber 21, which is filled with water. Chambers 22 and 23 are, preferably, 70 utilized for the liquid dyes and chamber 24 is filled with water. In the passage, successively, through the four chambers the yarns are wet in chamber 21 and are thus prepared to more readily take up the dye 75 in chambers 22 and 23 and are finally washed in the chamber 24.

Between the chambers 21 and 22 is a pair of weighted squeeze rolls 37—38 which operate to squeeze the major portion of the 80 water from the yarns as the latter pass on to the dye chamber 22. Between chambers 22 and 23 is a like pair of rolls 39—40, and also at the delivery end of the chamber 24 a like pair of rolls 41—42 by means of which 85 the dyed yarns are delivered from the machine in a semi-dried condition ready to be passed to, and wound upon, beams 43 or to be coiled in suitable cans.

In the chamber 21 are three idle rolls 21^a, 90 21^b, 21^c, the roll 21^b being located near the top of the liquid and the rolls 21^a and 21^c being located at or near the bottom of the liquid in said chamber.

Each of the chambers is provided with 95 like idle rolls, similarly located in said chambers, the said idle rolls being provided for the purpose of so guiding the yarns, in an indirect or angular course, in each chamber, that the yarns will be subjected to the influence of the liquids in said chambers a considerable length of time.

The driving control of my described machine is best seen in Fig. 2 of the drawings, the prime mover being pulley 44 which is 105 connected by belt 45, as here illustrated, with a pulley 46 on a horizontal shaft 47 that is revolvably supported in bearings secured to

the machine tank. Each pair of the described squeeze rolls is provided with a bevel gear 48, which meshes with, and is driven by, a bevel gear 49 secured to the shaft 47, the said rolls being thus driven at a uniform speed in order that they may serve as feed rolls for the yarns during the passage of the yarns through the machine and maintain the yarns under constant tension.

10 Between the chambers 21, 22 and 23 and the final washing chamber 24, the wetted and dyed yarns are caused to pass upward a considerable distance and over idler rolls 50 in order to remove surplus moisture or water and so that the color may be thoroughly oxidized by exposure, for a time, to atmospheric influence. From the roll 50 said yarns pass downward and through the washing chamber 24 and, as they leave said chamber, they 20 are squeezed by the rolls 41-42 and finally pass to the beams 43, or to cans, as may be desired.

15 My described apparatus and process operate automatically and continually and, 25 because of the constant and thorough agitation of the dyeing material by steam in prac-

tice passed therethrough, the yarns are colored from end to end with absolute uniformity.

Having thus described my invention, I 30 claim as new and wish to secure by Letters Patent.

1. Apparatus for dyeing yarns, including means for successively washing, dyeing and oxidizing the yarns, and guiding means for 35 said yarns, comprising a suspended element provided with eyes receiving said yarns, and an element including a plurality of slats over which pass said yarns in entering said apparatus, as stated.

2. An apparatus for dyeing yarns, including a plurality of washing and dyeing chambers, means for supplying dyeing material to one or more of said chambers, means for 45 passing yarns through said chambers and guiding means for said yarns, comprising a suspended member provided with eyes receiving said yarns and a frame equipped with a plurality of slats over which pass said 50 yarns in entering said chambers, for the purpose set forth.

CHARLES D. WHITE.
